UNITED STATES PATENT OFFICE.

GEORGE C. ST. LOUIS, OF FRESNO, CALIFORNIA.

AEROPLANE.

1,233,616.

Specification of Letters Patent. Patented July 17, 1917.

Application filed January 30, 1913, Serial No. 745,298. Renewed December 28, 1916. Serial No. 139,420.

To all whom it may concern:

Be it known that I, GEORGE C. ST. LOUIS, a citizen of the United States, residing at Fresno, in the county of Fresno and State of California, have invented new and useful Improvements in Aeroplanes, of which the following is a specification.

My invention relates to aeroplanes, having particular reference to improvements in steering mechanism or machines of the type above noted.

The principal object of my invention resides in the provision of novel steering rudders which may be conveniently operated from the driver's seat.

A further object is to provide steering rudders for both vertical and horizontal deflection of an aeroplane so forming and arranging the rudders that while offering very little resistance to the wind, they will at the same time add appreciably to the supporting surface of the machine.

The above and additional objects are accomplished by such means as are shown in their preferred embodiment in the accompanying drawings described in the following specification and then more particularly pointed out in the claims which are appended hereto and forming a part of this application.

In the drawings:

Figure 1 is a side elevation of an aeroplane equipped with my rudders.

Fig. 2 is a top plan view.

Fig. 3 is a rear elevation.

Fig. 4 is a front elevation.

Fig. 5 is a detail view showing the means by which the aft rudders are controlled.

Fig. 6 is a detail view showing the means by which the forward rudders are manipulated.

Referring now to the drawings throughout which similar references designate corresponding parts:

My invention includes in general the rudder supporting beam 1 and the fore and aft rudders designated as entireties by the numerals 2 and 3 respectively. The rudder supporting beam 1 is mounted centrally between the upper and lower planes and is held in spaced relation therefrom by the supporting rods 4 and 5. The rudder 2 is formed in two parts, the vertical member 6 being vertically disposed and in fixed relation to the member 1 and the horizontal blade designated by numeral 7 being pivot-

edly mounted on the forward portion of the beam. The blade 7 is formed in two parts, the one of which is disposed on the right hand side and the other of which is disposed on the left hand side of the blade 6. The right hand and left hand members of the blade 7, are designated in the drawings by the numerals 8 and 9, and are mounted on the shaft 10 which is revolubly seated in a lateral bore provided in the beam 1 and adjacent the forward end thereof. As a means for manipulating the rudder blade 7, I employ the bail members 11 and 12, the cables 13 and 14, the pulleys 15, 16, 17 and 18 and the lever 19. The bail members 11 and 12 are fixedly secured to the members 8 and 9, each of the said bail members being held against undue lateral movement by the contact of the bight portions of the bail with the supporting beam 1. The cable 13 is secured at one end to the bail 11 is passed through the pulleys 15, 16 and 18 and is subsequently secured to the lever 19 above the pivot point 20 thereof. The cable 14 is secured to the bail 12 and passes through the pulleys 17 and 18 and is secured to the lever below the pivot point 20.

Having described the construction of the forward rudder I shall now proceed to the description of the after rudder.

This rudder includes as does the forward rudder, a horizontal and a vertical blade designated by numerals 21 and 22 respectively. Differing from the forward rudder however, in this respect: whereas the horizontal blade 7 of the forward rudder is pivotally mounted, in the after rudder the horizontal blade 21 is stationary and the vertical blade 22 is pivotally mounted. It will be noted that the horizontal blade 21 and the horizontal blade 7 are of peculiar formation, the rear corners of the said blades being angularly and downwardly deflected.

To the blade 22, I have attached the bails 23 and 24, these bails being illustrated as right and left hand bails respectively. The cables 25 and 26 are connected to the bails 23 and 24 and are supported by and passed through the pulleys 27 and 28. These cables are then secured through the lever mechanism 29 which is identical in construction and operation with the lever 19 by which the forward blade 7 is operated. To permit the proper swinging movement, the blade 22 is pivotally mounted upon the rear end of the beam 1 and the swinging movement

thereof to accomplish the guiding action is permitted around this pivotal mounting.

In operating the steering device of my invention, the levers 19 and 29 are thrown either forwardly or backwardly as the case may be and thus draw the blade into the position desired through the medium of the bails and cables—for example—to cause the aero plane to rise, the lever 19 is thrown backward, drawing the blades 8 and 9 into an upwardly slanting position through the action of the cables upon the bails attached to said blades—then again, suppose it is desired to change the course to the left, the lever 29 is thrown forwardly, turning the blade 22 into the position desired through a similar action of the cables and bails secured thereto.

From the foregoing disclosure the construction and operation of my invention will be readily apparent.

It will of course be understood that various minor changes in details of construction and arrangement of parts may be made within the scope of the appended claims and without sacrificing any of the advantages of my invention.

What I claim is:

1. An aeronautical steering device including a supporting beam, a set of forward steering blades, horizontally and vertically disposed, the vertically disposed of said forward blades being in fixed relation to the supporting beam, the horizontally disposed of said forward blades being pivotally mounted thereon, the rear corners of said horizontal blade being angularly and downwardly deflected and means carried by said horizontal blade and said supporting beam for controlling the said horizontal blade, for the purpose set forth.

2. An aeronautical steering device including a supporting beam to be mounted longitudinally of a machine, a set of rearward steering blades horizontally and vertically disposed, the horizontally disposed of said rearward blades being in fixed relation to the supporting beam, a pivotal mounting between vertically disposed blade and

the supporting beam provided near one end 50 of said vertical blade, the rear corners of said horizontally fixed blade being angularly and downwardly deflected, and means carried by said pivotally mounted blade to embrace and to have movement with respect 55 to said supporting beam to be operated to cause deflection of said pivoted blade to accomplish a steering or swinging of said blade and means to cause actuation of said blade deflecting means.

3. An aeronautical steering device including a supporting beam, a set of forward steering blades horizontally and vertically disposed, a pivotal connection between the forward ends of the horizontally disposed 65 blades and said supporting beam, a rear corner of each of said horizontal blades being angularly and downwardly deflected, bails secured to said horizontal blades and embracing said supporting beam, cables 70 connected with said bails, and a lever with which said cables have connection and by which movement may be transmitted to the horizontally disposed blades to cause swinging 75 thereof around said pivotal connection.

4. An aeronautical steering device including a supporting beam adapted to be mounted longitudinally of a machine and to project from the rear thereof, a set of rearward steering blades horizontally and vertically 80 disposed, the vertically disposed of said steering blades provided with a pivotal mounting adjacent the rear edge thereof upon said supporting beam, bails attached to the free swinging end of said vertical 85 blade to bridge around said supporting beam and permit swinging movement of said pivotally mounted blade, cables attached to said bails, and an operating lever with which said cables have attachment and by which 90 movement may be transmitted to the bails to swing the pivotally mounted blade in one direction or the other to accomplish steering action.

GEORGE C. ST. LOUIS.
